UNITED STATES PATENT OFFICE

168,576

VEHICLE FRONT END ASSEMBLY

Fred A. Lee, Fort Wayne, Ind., assignor to International Harvester Company, a corporation of New Jersey

Application July 15, 1950, Serial No. 11,214

Term of patent 14 years

(Cl. D14—3)

To all whom it may concern:

Be it known that I, Fred A. Lee, a citizen of the United States, residing at Fort Wayne, in the county of Allen and State of Indiana, have invented a new, original, and ornamental Design for a Vehicle Front End Assembly, of which the following is a specification, reference being had to the accompanying drawings, forming part thereof, in which:

Figure 1 is a perspective view taken from one side of a vehicle front end assembly, showing my new design;

Figure 2 is a perspective view taken from the other side thereof; and

Figure 3 is a front elevational view thereof.

The dotted lines on the drawings are for illustrative purposes only.

I claim:

The ornamental design for a vehicle front end assembly, substantially as shown and described.

FRED A. LEE.
